CIRCUIT ARRANGEMENT FOR GENERATING
A SAWTOOTH-SHAPED CURRENT IN A
COIL

Bernardus Willem van Ingen Schenau, Eindhoven, Netherlands, assignor to Hartford National Bank and Trust Company, Hartford, Conn., as trustee

Application March 26, 1948, Serial No. 17,246
In the Netherlands April 21, 1947

3 Claims. (Cl. 315—27)

1

The invention relates to a circuit-arrangement for producing in a coil a sawtooth-shaped current with the aid of a discharge tube to which a sawtooth-shaped voltage is supplied, wherein the anode circuit of this tube includes the primary winding of a transformer and the coil is connected to a secondary winding of this transformer, a diode being connected into the said circuit so as to be conductive during the stroke of the sawtooth-shaped current.

In the known circuit-arrangements of this kind the cathode of the diode, usually referred to as "efficiency-diode," is connected to that point of the circuit at which during the fly-back of the current occurs in the anode circuit the high-pulse-voltage of, for example, 4000 volts or upwards, the said point being that end of the primary winding of the transformer which is located near the anode of the discharge tube.

The fly-back time of the sawtooth-current is determined by the first half-period of the natural oscillation of the circuit formed by the self-induction of the transformer and the capacities of the latter and of the tube and the wiring system and mostly this time should be as short as possible. To that end use must be made of a winding having only little capacity and, moreover, the supply of the cathode of the efficiency-diode must be effected in a substantially capacity-free manner, which, on account of the fact that, in addition, this supply must be realised in an insulated manner with respect to the high pulse-shaped voltages produced, entails additional difficulties.

The circuit-arrangement according to the invention obviates these disadvantages and exhibits the feature that the cathode of the diode is connected to that end of the primary transformer winding which is remote from the anode of the discharge tube, and that a second secondary transformer winding is included in the anode circuit of the diode.

With this circuit-arrangement the cathode of the diode is consequently connected to a point at which occurs only a comparatively low direct-voltage, viz. the positive voltage of the anode-voltage source of the discharge tube, so that the supply of this cathode does not entail additional disadvantages.

The invention will be explained more fully with reference to the accompanying drawing in which Fig. 1 represents, by way of example, a circuit-arrangement according to the invention. Fig. 2 represents, by way of example, a transformer for use in Fig. 1.

2

Input terminals 1 and 2 of the control-grid circuit of a discharge tube 3 in Fig. 1 have supplied to them a sawtooth-shaped voltage which is taken, for example, from a blocking oscillator. For example, in a circuit-arrangement for a television-receiver this oscillator may be synchronized by the supply of line synchronizing pulses. The anode circuit of the tube includes the primary winding 4 of a transformer 5 to the secondary winding 6 of which are connected deflector coils 7 destined to bring about, for example, the horizontal deflection of the cathode ray beam of a cathode ray tube.

The transformer 5 comprises another secondary winding 8 which is included in the anode circuit of an efficiency-diode 9 the cathode 10 of which is connected to the positive terminal 11 of an anode voltage supply 12, the cathode 10 being consequently connected at the same time to that end of the primary transformer winding 4 which is remote from the anode of the tube 3.

It will be evident that during the stroke of the sawtooth-shaped current in the coils 7, when consequently the anode current of the discharge tube 3 increases linearly and, due to the self-induction of the winding 4, the anode voltage has decreased by a certain amount, the voltage across the winding 8 has increased by a certain amount, so that the efficiency-diode is conductive and consequently there occurs an effect similar to that occurring in the known circuit-arrangements.

It may be noted that, for obtaining a circuit-arrangement with which a low voltage is applied to the cathode of the diode 9, it is not necessary to use a transformer comprising three windings. Alternatively, the deflector coils 7 may be coupled directly to the winding 8, in which event, however, high voltages are set up across the coils 7. If, on the other hand, we wanted to avoid this disadvantage by means of another transformation ratio between the windings 4 and 8, the diode 9 must have a low internal resistance, which can be realised with great difficulty only.

According to one advantageous embodiment of a circuit-arrangement according to the invention, the transformer is constructed in such manner that no coupling or substantially no coupling exists between the stray self-induction of the primary winding 4 with respect to the second secondary winding 8, on the one hand, and that of the latter winding with respect to the other secondary winding 6 to which the deflector coils are connected, on the other hand, for it has been found that due to the existence of coupling between these stray self-inductions

any disturbing oscillation occurring in the transformer windings 4 and 8 is transmitted to the deflecting circuit with the result that the regularity of the line-raster on the screen of the cathode ray tube is disturbed.

In spite of the production of such disturbances in the windings 4 and 8 a line raster free of disturbances may now be described if the coupling between the stray self-inductances of the winding 4 with respect to the winding 8 and of the latter 10 winding with respect to the winding 6 is eliminated.

Fig. 2 represents, by way of example, a transformer for use in a circuit-arrangement according to the invention. A cylindrical core 13 of magnetic material has provided on it a secondary winding 14 which extends for a distance smaller than the length of the core. The coils 7 of Fig. 1 are connected to this winding. Outside thereof is provided the secondary winding 15, which is included in the diode circuit and which extends over a distance exceeding the length of the winding 14. The winding 15 is surrounded by the primary winding 16. With such a construction of the transformer coupling between the stray self-induction of the winding 15 with respect to the winding 16 and the stray self-induction of the winding 14 with respect to the winding 15 may substantially completely be avoided.

What I claim is:

1. An electrical circuit arrangement for producing a saw-tooth shaped current in the deflection coil of a cathode ray tube, comprising an electron discharge tube having a cathode, a control grid and an anode, means to apply a saw-tooth shaped voltage to the cathode and control grid, a transformer comprising a high impedance primary winding having the ends thereof spaced apart and having one end thereof connected to the anode, a low impedance secondary winding and a high impedance tertiary winding, a source of potential having the negative pole thereof connected to the cathode and having the positive pole thereof connected to the other end of said primary winding, means to couple the secondary winding to the said deflection coil, and a diode element having a cathode connected to the end of the primary winding remote from the said anode and having an anode connected to said tertiary winding.

2. An electrical circuit arrangement for producing a saw-tooth shaped current in the deflection coil of a cathode ray tube, comprising an electron discharge tube having a cathode, a con-

trol grid and an anode, means to apply a saw-tooth shaped voltage to the cathode and control grid, a transformer comprising a high impedance primary winding having the ends thereof spaced apart and having one end thereof connected to the anode, a low impedance secondary winding and a high impedance tertiary winding having the ends thereof positioned adjacent the respective ends of the primary winding, a source of potential having the negative pole thereof connected to the cathode and having the positive pole thereof connected to the other end of said primary winding; means to couple the secondary winding to the said deflection coil, and a diode element having a cathode connected to the end of the primary winding remote from the said anode and having an anode connected to the end of the tertiary winding remote from the anode end of the primary winding.

3. An electrical circuit arrangement for producing a saw-tooth shaped current in the deflection coil of a cathode ray tube, comprising an electron discharge tube having a cathode, a control grid and an anode, means to apply a saw-tooth shaped voltage to the cathode and control grid, a transformer comprising a core member, a low impedance secondary winding wound on said core, a high impedance tertiary winding superimposed on said secondary winding and a high impedance primary winding superimposed on said secondary winding, having the ends thereof spaced apart and having one end thereof connected to the anode, a source of potential having the negative pole thereof connected to the cathode and having the positive pole thereof connected to the other end of said primary winding, means to couple the secondary winding to the said deflection coil, and a diode element having a cathode connected to the end of the primary winding remote from the said anode and having an anode connected to said tertiary winding.
